LOOSE LEAF POST BINDER HANGER AND CARRIER

Henry V. Ivory, Chatham, N.J., assignor to Boorum &
Pease Company, Brooklyn, N.Y.

Filed July 17, 1972, Ser. No. 272,121

Term of patent 14 years

Int. Cl. D8—06

U.S. Cl. D8—154

FIG. 3

FIG. 2

FIG. 1

FIG. 1 is a front elevational view of a loose leaf post binder hanger and carrier showing my new design;

FIG. 2 is a bottom plan view; and

FIG. 3 is a side elevational view.

The opposite side elevational views not shown are mirror images of those shown.

I claim:

The ornamental design for a loose leaf post binder hanger and carrier, as shown.
